UNITED STATES PATENT OFFICE.

ROBERT DUNSEATH, OF NEW YORK, N. Y.

COLLAPSIBLE BLOCK.

1,271,869.

Specification of Letters Patent.

Patented July 9, 1918.

Application filed April 6, 1918. Serial No. 227,015.

To all whom it may concern:

Be it known that I, ROBERT DUNSEATH, a citizen of the United States, and a resident of New York, in the county of New York and State of New York, have invented a certain new and useful Improvement in Collapsible Blocks, of which the following is a full, clear, and exact specification.

This invention relates more particularly to a hoisting block of a class disclosed in my Patent No. 1,146,411, dated July 13, 1915.

The invention has for its object primarily to provide a block adapted to be employed with a cable or line for hoisting and lowering articles especially of heavy weights to various heights, and which is of a collapsible type whereby its parts may be separated to allow the device to be easily transported, besides allowing the device to be enlarged or reduced in size as well as permitting parts of the device when damaged to be replaced with new parts. This is accomplished mainly by providing two or more corresponding plates, each having one or a number of spaced openings, and the openings of each plate are in register with the openings of the other plates. In each series of the registered openings is a removable bolt, and each bolt is composed of a like number of sections formed so as to be detachably connected to allow the bolts to be increased and reduced in lengths as well as providing spaced annular grooves at the joints of the sections so that plates may be removably mounted in the grooves and so that sheaves may be removably mounted on one of the bolts between the plates.

A further object of the invention is to provide a hoisting block of a simple and efficient construction, and which is susceptible of being made in any desired shape and size so as to combine great strength and durability.

A practical embodiment of the invention is represented in the accompanying drawings forming a part of this specification in which similar characters of reference indicate corresponding parts in all the views, the said invention being more fully described hereinafter, and then pointed out in the claims at the end of the description.

In the drawings Figure 1 is a side elevation of one form of collapsible block embodying my invention.

Fig. 2 is a sectional view taken on the line 2—2 of Fig. 1.

Fig. 3 is an elevation of one of the plates used in the block.

Fig. 4 is a longitudinal vertical section, partly in detail, taken through a form of 60 the block of a reduced size to the block shown in Fig. 2, and

Fig. 5 is an enlarged side view, partly broken away, of one of the bolts with its sections separated from each other. 65

The collapsible block has two side plates 10 and 11, and as occasion requires forms of the block may be provided having one or a suitable number of intermediate plates as 12, 13, 14. These plates may be of any 70 shape and size according to the size of the block desired, and all of the plates are of corresponding formations. Through the centers of all the plates are registered holes 15, and through the lower parts of all the 75 plates are registered holes 16, while through the upper parts of all the plates are also registered holes 17.

In the series of registered holes 15 is a bolt 18, while in the series of registered 80 offices 16 is a secured bolt 19, and in the series of registered holes 17 is a third bolt 20. The bolts may be similar in diameters or the bolts may vary in diameters, and when a block is assembled with only two end 85 plates, or when a block is assembled having the end plates, besides having a number of the intermediate plates the three bolts are of corresponding lengths according to the size of the block provided. Each of the bolts 90 is composed of a key section 21, and a like number of corresponding sections, as 22, 23, 24. The key section 21 of each bolt has a cylindrical axle portion 25, and projecting in alinement in opposite directions from the 95 ends of the axle portion of each key section are cylindrically-shaped lugs or extension members 26 and 27. These lugs of the key section of each bolt are considerably less in diameters than the axle portion of the bolt, 100 and the free end parts of these lugs are exteriorly threaded, as at 28 and 29, respectively. Each of the sections 22, 23, 24 of each bolt has also a cylindrical axle portion 105 30, and protruding from one end of each axle portion is a cylindrically-shaped lug or extension member 31 having its free end part exteriorly threaded, as at 32, while in the center of the second end of each axle portion is an interiorly threaded recess 33. The 110 axle portions of the sections of each of the bolts 21, 22, 23, 24 are similar in diameters as

well as being of similar lengths. The threaded lugs of the sections of each bolt are also of corresponding diameters and lengths, and the threaded recesses 33 of the sections 5 22, 23, 24 of each bolt are of diameters to allow the threaded lugs to be screwed thereto. Through each of the threaded lugs of each section of each bolt may be an aperture 33^a to permit a wrench or other implement 10 to be used for conveniently screwing the section to one of the other sections, and in this manner each of the bolts 18, 19, 20 is extensibly formed so that the bolts may be reduced or increased in lengths for providing 15 blocks of various sizes. Moreover, by threading only portions of the lugs of the sections of each bolt the sections of each bolt when detachably connected will be spaced apart to provide each bolt with one or more 20 annular grooves, as 34, except when a block is assembled having bolts formed by using in each bolt only the key section 21.

When a block is provided having the side plates 10 and 11 with a number of the intermediate plates, as illustrated in Figs. 2 and 25 5, each of the three bolts is formed by passing through the holes 15, 16, 17 of one of the side plates 10 and 11 one of the threaded lugs of the key sections 21 of the bolts. On 30 the axle portion 25 of the key section of the bolt 18 is disposed a sheave or grooved pulley 35 so as to freely revolve on the bolt. The second threaded lugs of the key sections of all the bolts are passed through the holes 35 15, 16, 17 of one of the intermediate plates 12, 13, 14, and on the ends of the second threaded lugs of each of the key sections is screwed the recessed axle portion 30 of one 40 of the sections 22, 23, 24 of the bolts. A second sheave or grooved pulley 36 is arranged on the recessed axle portion of the section 22 of the bolt 18 so as to freely revolve thereon, and the threaded lugs of these sections of all the bolts are passed 45 through the holes 15, 16, 17 of another of the intermediate plates. On the free ends of the lugs of each of the sections 22 of the bolts is screwed the recessed axle portion 30 of one 50 of the sections 23 of the bolts, and on the axle portion of this section of the bolt 18 is arranged a freely revoluble sheave or grooved pulley 37. The third of the intermediate plates is disposed on the lugs of the sections 23 of all the bolts, and the recessed 55 axle portions of the sections 24 of the bolts are screwed on the threaded free ends of the lugs of the sections 23. Still another sheave or grooved pulley 38 is arranged to revolve on the recessed axle portion 30 of the section 24 of the bolt 18, and the second side plate is then disposed on the lugs of these sections of all the bolts. The threaded lugs of the sections of the extensible bolts 18, 19, 20 are of lengths to permit of this manner of 60 assembling the parts of the block, and the 65

lugs are also of lengths so that those disposed in the holes of the side plates 10 and 11 will protrude some distance beyond the side plates. The annular grooves 34 of the bolts are of widths so that the intermediate 70 plates will be tightly held therein, while the axle portions of the sections of the bolts are of widths to space all of the plates apart so that the sheaves will revolve freely but closely between the plates. On the threaded 75 ends of the lugs of each bolt which protrude beyond the side plates 10 and 11 are screwed nuts, as 39 and 40, and through each nut may be an opening 41 to allow the use of a spanner wrench or other implement for 80 easily rotating the nuts. If desired on the bolt 18 of the block during the assembling of the parts of the block, as above described, may be arranged a shackle, as 42, for use as occasion requires. Thus, I provide a collapsible block designed to be employed in conjunction with a line or cable for hoisting and lowering articles to different heights, and which is adapted to be separated into parts for convenient transportation as well 90 as permitting a limited number or all of the parts to be used whereby blocks of different sizes may be provided, besides allowing one or more of the parts when damaged to be replaced with new parts. 95

In the foregoing description, I have embodied the preferred form of my invention, but I do not wish to be understood as limiting myself thereto, as I am aware that modifications may be made therein without departing from the principle or sacrificing any of the advantages of this invention, therefore I reserve to myself the right to make such changes as fairly fall within the scope thereof. 100

Having thus described my invention, I claim as new and desire to secure by Letters Patent—

1. A block of the character described, comprising spaced plates each having a hole 110 in register with the holes of the other plates, bolts removably disposed in the registered holes of the plates and the bolts being composed of a number of detachably connected sections, sheaves rotatable on the bolt between each pair of the plates, and means on all the bolts releasably fastening the plates and the bolts together. 115

2. A block of the character described, comprising spaced plates each having spaced holes and the holes of each plate being in register with the holes of the other plates, a bolt removably disposed in each series of the registered holes of the plates and each bolt being composed of a like number of 120 detachably connected sections, sheaves rotatable on one of the bolts between each pair of the plates, and means on all the bolts releasably fastening the plates and the bolts together. 125

3. A block of the character described, comprising spaced plates each having a hole in register with the hole of the other plates, a bolt removably disposed in the registered holes of the plates and the bolt being composed of two detachably connected axle portions between the plates and two of the axle portions having lugs removably inserted in the holes of the end plates, and a sheave 10 freely revoluble on each axle portion of the bolt.
4. A block of the character described, comprising two spaced side plates and an intermediate plate each having spaced holes 15 and the holes of each plate being in register with the holes of the other plates, a bolt removably disposed in each series of the registered holes of the plates and each bolt being composed of two detachably connected 20 axle portions between the plates and each axle portion having a lug removably inserted in the holes of the side plates, and a sheave freely revoluble on each axle portion of one of the bolts.
- 25 5. In a block of the character described, a bolt composed of a key section having a cylindrical axle portion and having two threaded lugs projecting in opposite directions from opposite parts of the axle portion, and a separate interiorly threaded re-
- cessed axle portion screwed on one of the lugs of the first named axle portion so that both of the axle portions are in spaced relation, said second axle portion having a threaded lug projecting in an opposite direction and in 35 alinement with the second lug of the first mentioned axle portion.
6. In a block of the character described, a bolt composed of a key section having a cylindrical axle portion, including two 40 threaded lugs of less diameters than the axle portion projecting in opposite directions from the ends of the cylindrical portion, and a plurality of separate corresponding sections, each having a cylindrical axle portion, 45 including a threaded recess in one end of each axle portion as well as having a threaded lug of less diameter than the axle portion protruding from its second end and said recesses and lugs being of relative sizes whereby the recessed axle portion of each of the recessed sections may be removably screwed on the lug of one of the other sections so that all the axle portions will be spaced apart.
- 50 This specification signed and witnessed 55 this 5th day of April, A. D. 1918.

ROBERT DUNSEATH.
